UNITED STATES PATENT OFFICE.

GEORGE STEINGRUBER, OF ATLANTA, GEORGIA.

GLARESHIELD FOR AUTOMOBILE HEADLIGHTS.

Application filed August 22, 1925. Serial No. 51,783.

This invention relates to a glare shield for automobile headlights, and particularly to a construction of screen adapted to be applied to the light bulb within a reflector.

In this type of screen the solid body usually enclosing the upper portion of the light bulb materially reduces the illuminating capacity of a lamp of given candle power and practically prevents any reflective action from the upper portion of the usual conical or parabolic reflector. This objection I have overcome by providing an open portion extending rearwardly from the screen at the apex of the bulb to the shank of the bulb so that substantially the entire central body of the lamp is exposed for the reflection of the light rays therefrom into contact with the reflector while the screen prevents the upward and outward rays which may not engage the reflector surface from being projected.

While these screens may be of a solid material, still I have found it most desirable to form them of a translucent material preferably colored so that a portion of the illuminating effect of the lamp passes through the screen and is so toned by the color medium as to prevent glare and provide an illuminated surface easily viewed by the operator of an approaching machine. In the mounting of such spherical bulb screens difficulty has been found in securing them in proper position due to the vibration of the machine, and in order to effectually dispose the shield in proper position and secure it against any movement a shank is provided thereon which extends between the lamp and its socket and is provided with apertures for the adjustment of the screen upon the pin of the lamp which interlocks with the socket in the usual manner. By this means the screen is held against any rotative or longitudinal movement and by its disposition between the lamp and socket is firmly sustained against vibration, and the lamp itself is protected against breakage from the usual vibration due to loose fitting.

The invention has for an object to provide a spherical bulb screen having a supporting shank at its rear and a light intercepting portion above the apex of the bulb with a cut-away sector extending from said portion to the supporting shank at the rear.

A further object of the invention is to provide a spherical screen adapted to be mounted upon a lamp bulb and formed of a

translucent material, the rear of said screen being open to permit passage of light rays therefrom to the reflector.

Another object of the invention is to provide an improved mounting for a bulb screen comprising a shank adapted to be disposed between the lamp bulb and its socket and provided with means for interlocked connection with the bulb to prevent relative movement thereof.

Other objects and advantages of the invention will be hereinafter set forth and the novel features thereof defined by the appended claims.

In the drawings:

Figure 1 is a horizontal section with the screen in assembled position;

Figure 2 is a vertical section of the same;

Figure 3 is a detail side elevation of the screen;

Figure 4 is a top plan thereof;

Figure 5 is a detail section of the interlocked connection between the screen and bulb socket; and

Figure 6 is a detail elevation of the screen shank in its relation to the locking pin of the bulb.

Like reference numerals designate corresponding parts throughout the several figures of the drawings.

The light screen is adapted for application to any desired form of lamp and reflector but it is particularly designed for use in an automobile headlight where the usual conical or parabolic reflector 10 is used and the electric bulb 11 disposed at substantially the axial center thereof. The base 12 of this bulb is formed with the usual locking pin 13 which engages in the slots 14 of the socket 15 which supports the lamp in position.

The screen 16 is adapted to be supported between the base of the lamp and the socket and comprises a semi-spherical portion 17 at the front which is projected inward upon a curved line 18 at its upper edge so as to cover and shield the direct rays from the outer portion of the lamp which would otherwise be projected upward and outward to effect a glare objectionable and dangerous to an approaching operator or pedestrian. The portion 16 of the screen is extended inward to form a supporting shank 19 which is provided with a series of securing apertures 20 any one of which may be fitted over the pin 13 from the lamp base in the adjustment of the screen into proper

relation with the bulb. This shank is inserted between the lamp base and its socket and thus takes up the usual slack or looseness in the lamp and prevents vibration both 5 of the bulb and of the screen.

The lower face of the screen is formed with a horizontal flange 21 to impart rigidity thereto while the portion of the screen from the body 17 to the shank 19 is cut 10 away as at 22 to expose substantially the entire upper portion of the lamp to the reflecting surface above the same and thus utilize the full illuminating capacity of the lamp by the reflected direction of the rays 15 at the rear of the apex thereof.

This screen is formed of non-reflective material as it has been found that a reflective action therefrom materially affects the proper direction of the light rays in 20 focusing the lamp so as to dispose them in a horizontal plane within a fixed elevation as required by most automobile lighting regulations. While the screen may be formed of solid material, it is preferably constructed 25 of a translucent material, such as celluloid, and may be suitably colored to tone the light rays passing therethrough, in which event the body 17 intercepts sufficient of the direct rays to prevent a glare but also 30 becomes an illuminated surface from which colored rays are projected to the reflector and are visible when viewing the lamp from the front. The disposition of this body or shield portion is such that the filament of 35 the lamp is not visible to an observer from any angle when facing the reflector.

While the specific construction of the screen and its attaching means have been shown and described, still the invention is 40 not confined thereto as changes and alterations may be made without departing from the spirit thereof as defined by the appended claims.

Having thus described my invention, 45 what I claim as new and desire to secure by Letters Patent is:—

1. A glare screen comprising a body having a semi-spherical screen, and a supporting shank extended radially from the rear 50 of said body and constructed to be inter-

posed longitudinally between the base of a lamp bulb and its socket.

2. A glare screen comprising a body having a semi-spherical screen and a supporting shank extended radially from the rear 55 of said body and constructed to be interposed longitudinally between the base of a lamp bulb and its socket, and means upon said shank interlocking with cooperating means upon the lamp base to prevent relative movement of the parts.

3. A glare screen comprising a translucent semi-spherical screen member and a curved shank extending radially therefrom and constructed to be interposed longitudinally 60 between the base of a lamp bulb and its socket.

4. A glare screen comprising a translucent semi-spherical screen member and a curved shank extending radially therefrom 70 and constructed to be interposed longitudinally between the base of a lamp bulb and its socket, said screen being extended forwardly to partially enclose the front of a lamp bulb.

5. A screen for a lamp bulb provided with a light intercepting body and a shank formed for longitudinal insertion between the base of the bulb and the inner face of its socket, and means upon said shank and base for adjustably connecting the shank thereto.

6. In a headlight reflector, the combination with a lamp and its socket having interlocking pin connection, of a screen provided 85 with a shank adapted to be disposed between the lamp and the inner wall of the socket and provided with an aperture to fit over said pin.

7. A screen for a headlight bulb comprising a semi-spherical body and a curved attaching shank to enter the bulb socket and provided with a circumferential series of apertures, said screen being cut away between said body and shank to expose a 95 material portion of the bulb to the enclosing reflector.

In testimony whereof I affix my signature

GEORGE STEINGRUBER.
